UNITED STATES PATENT OFFICE.

ALBERT WAKEFIELD, OF WASHINGTON, DISTRICT OF COLUMBIA.

PROPELLER.

1,206,058.

Specification of Letters Patent. Patented Nov. 28, 1916.

Application filed December 6, 1915. Serial No. 65,384.

To all whom it may concern:

Be it known that I, ALBERT WAKEFIELD, a citizen of the United States, residing at Washington, in the District of Columbia, 5 have invented certain new and useful Improvements in Propellers, of which the following is a specification.

This invention relates to propellers, and its object is to provide a propeller of novel 10 and improved design whereby a maximum efficiency is obtained.

In order that the invention may be better understood, reference is had to the accompanying drawing, in which—

15 Figure 1 is a side elevation of the propeller; Fig. 2 is an end view thereof, and Fig. 3 is an end view of one of the propeller blades showing a modified structure.

Referring specifically to the drawing, 10 20 denotes a hub or shaft from which the blades of the propeller radiate, said blades being formed integral with the hub, or made separate therefrom and rigidly secured in any approved manner. The drawing 25 shows a six-bladed propeller, the blades being set obliquely as usual. The blades are arranged in staggered order so that each blade is given its own water and there is no interference between the blades. It will be 30 understood, of course, that the number of blades employed may be varied.

The back of each blade, throughout its entire length, from the hub to the tip, is flat, this portion of the blade being indicated 35 at 11, and extending from the leading edge 12 of the blade up to within a short distance from the back or following edge 12^a, the blade being then given a slight transverse curvature, as indicated at 13, this curvature 40 extending throughout the entire length of the blade and from the flat portion 11 up to the back edge 12^a, and the convexity being on the back or rear face of the blade.

On the driving face or side of the blade 45 are parallel longitudinal corrugations or ridges 14 extending from the hub portion of the blade to the tip. These corrugations define a series of inclines 15 sloping in opposite directions, the last inclines merging 50 with the edges of the blade. The driving

face is thus given a series of working surfaces resulting in a powerful thrust on the medium in which the propeller works, and obtaining a maximum driving force. It will be noted in Fig. 3 that the spacing of the 55 working surfaces from the back of the blade is not uniform but increases from the leading to the following edge. Each working surface is therefore offset relative to the next one, and is thus given its own water, and 60 there is no interference between said surfaces. The corrugations are highest at the following edge of the blade, and they progressively decrease in height toward the leading edge, so that the cross section of the 65 blade is that of a wedge. The faces of the corrugations on the following edge of the blade have a steeper inclination as compared with those of the leading edge. The blade may be made solid, or hollow as shown 70 in Fig. 3.

I claim:—

1. A propeller blade having on its driving face a series of corrugations, the faces of the corrugations on the following edge 75 of the blade having a steeper inclination as compared with those of the leading edge.

2. A propeller blade having on its driving face a series of corrugations, the faces of the corrugations on the following edge 80 of the blade having a steeper inclination as compared with those of the leading edge, and said corrugations being offset relative to each other.

3. A propeller blade which is wedge- 85 shaped in cross-section, the taper being toward the leading edge of the blade, and the driving faces of the blade having a series of corrugations, the faces of said corrugations on the following edge of the blade hav- 90 ing a steeper inclination as compared with the leading edge.

In testimony whereof I affix my signature in presence of two witnesses.

ALBERT ^{his} X WAKEFIELD.
